UNITED STATES PATENT OFFICE

2,452,751

APPARATUS FOR RECEIVING AND
DUMPING REFUSE

Warren D. Hardy, Roanoke, Va.

Application November 6, 1946, Serial No. 708,088

1 Claim. (Cl. 214—120)

1
My present invention relates to an improved apparatus for receiving and dumping refuse and more particularly to an elevated container for garbage and ashes, provided with elevating means for raising and dumping the refuse, and means for emptying the container through a chute directly into a collecting vehicle.

In the accompanying drawings I have illustrated one complete example of the physical embodiment of my invention according to the best mode I have thus far devised, but it will be understood that various changes and alterations may be made in the exemplified structure within the scope of the appended claim.

In the drawings:

Fig. 1 is a side elevational view of the apparatus of my invention.

Fig. 2 is a front elevational view thereof.

Fig. 3 is a rear elevational view.

Fig. 4 is a top plan view.

Fig. 5 is a horizontal sectional view at line 5—5 of Fig. 2.

Fig. 6 is a detail view of the arrangement for the elevating bracket; and Fig. 7 is a vertical sectional view thereof at line 7—7 of Fig. 6.

Fig. 8 is a detail view of the chute and the container doors for releasing the refuse therein.

Referring now to the drawings I utilize a skeleton framework including the vertical posts 2, horizontal bars 4, and braces 6 mounted upon concrete bases 8.

Atop this framework which may be of suitable height to prevent access thereto, I provide a hopper having sections 10 and 12 separated by a wall or partition 13 as for ashes and garbage and the common bottom 14 of these sections is shaped as shown. Aligned with the sloping bottom 14 is a stationary chute 16 having converging side walls 18 and 20, and an extension chute 22 is pivoted thereto as at 24, and raised by rope 25 on sheave 25'. Doors or gates 26 and 28 for the hopper sections 10 and 12 are suitably guided and may be raised by pulling down on the ropes 30 and 32 which extend over sheaves 34 and 36, dumping the contents through the extended chute 22 into a waiting collection truck.

The rear walls 38 and 40 of the containers are provided with horizontally pivoted swinging doors 42 and 44 which close under their own weight, and to charge the containers I provide an elevating mechanism conveying bucket 46 supported by rope 48 through sheave 50 which is freely movable on the rod 52. The rear of the frame is fashioned with three vertical guides 54, 56 and 58 forming two juxtaposed guideways for the bucket and 55

when ashes or garbage is placed in the bucket, it is aligned so that lugs 59 engage in the proper pair of guides, and the sheave 50 is adjusted accordingly.

5 The carrier is then raised by rope 48, and when the lugs reach the upper closed ends of the guide continued pulling on the rope 48 will trip the bucket as seen in Fig. 2 thereby dumping the buckets into the selected section of the hopper.

10 The hopper sections 10 and 12 are formed with baffle plates 62 and 64 to prevent lodging of refuse in the corners and it will be apparent that the use of the apparatus of my invention will obviate the need for garbage and ash cans, and will eliminate 15 the handling of such refuse by collection personnel.

Dogs and cats will be unable to reach the contents, and the result of the use will be an improvement in health and ease of removal.

20 Having thus fully described my invention what I claim as new and desire to secure by Letters Patent is:

In a domestic refuse elevator, the combination which comprises a vertically disposed frame 25 tangentially shaped in plan having posts at the four corners supported by suitable bracing elements, a hopper having a sloping floor with sloping sides and having a longitudinally disposed partition therein dividing the interior into separate sections, said hopper supported by the frame in spaced relation above the ground, a plurality of vertically disposed parallel rails providing upwardly extending tracks on the side of the frame corresponding with the high side of the hopper, a 30 supporting bar suspended above the upper end of the hopper and extended laterally to bridge the said tracks, a pulley block slidably mounted on the bar, a carrier having a bail on the upper end and extensions on one side positioned to coact with the rails of either of the tracks whereby the rails hold 35 the carrier against outward movement away from the frame, trips at the upper ends of each of said tracks for actuating the carrier to dumping position, as the carrier reaches the upper ends of the 40 tracks whereby the contents of the carrier are dumped into the sections of the hopper respectively, a common chute pivotally mounted on the lower side of the hopper and positioned to receive materials from each section thereof, gates in the sections of the hopper and on the low side thereof, 45 and suitable cables for operating the carrier, chute and gates of the hopper.

WARREN D. HARDY.
